DESIGN FOR A PLAQUE FOR AUTOMOBILES OR THE LIKE

Stanley H. Ross, Scarsdale, N. Y.

Application February 4, 1942, Serial No. 105,633

Term of patent 3½ years

To all whom it may concern:

Be it known that I, Stanley H. Ross, a citizen of the United States and a resident of Scarsdale, county of Westchester, and State of New York, have invented a new, original, and ornamental Design for a Plaque for Automobiles or the like, of which the following is a specification, reference being had to the accompanying drawing, forming part thereof, in which—

Figure 1 is a front view of a plaque for automobiles or the like, showing my new design; and Figure 2 is a top plan view thereof.

I claim:

The ornamental design for a plaque for automobiles or the like, substantially as shown.

STANLEY H. ROSS.
